UNITED STATES PATENT OFFICE.

CHARLES HORACE HILL, OF SCRANTON, PENNSYLVANIA.

HYDRAULIC AIR-COMPRESSOR.

SPECIFICATION forming part of Letters Patent No. 292,814, dated February 5, 1884.

Application filed July 16, 1883. (No model.)

To all whom it may concern:

Be it known that I, CHARLES H. HILL, a citizen of the United States, residing at Scranton, in the county of Lackawanna and State of Pennsylvania, have invented a new and useful Hydraulic Air-Compressor, of which the following is a specification, reference being had to the accompanying drawing.

This invention relates to hydraulic air-compressors, and it has for its object to produce a device which shall possess superior advantages in point of simplicity, durability, and general efficiency.

To this end it consists in certain improvements in the construction of the same, which will be hereinafter fully described, and particularly pointed out in the claims.

In the drawing hereto annexed the single figure represents a vertical sectional view of my improved hydraulic air-compressor.

A designates a tank or cylinder, closed at the top, and having at the bottom an annular flange, B, resting against the bottom or base plate, C, a gasket, D, of rubber or other suitable packing, being interposed.

E is a ring resting upon the flange B, and having a downwardly-extending annular flange, F, encircling the flange B, gasket D, and the base-plate, and making a tight joint. The fastening screws or bolts G pass through the ring E, flange B, gasket D, base C, and also through the legs G², three or more of which may be used, and which are in this manner secured in position to support the tank or cylinder A.

The bottom plate, C, is provided with the water-inlet I and waste-pipe J. Near the former is located an upright, K, to which is fulcrumed a lever, L, the ends of which are provided with valves M N, adapted to close, respectively, the inlet I and the waste-pipe J. In the drawing the latter is shown closed, while the inlet is unobstructed.

O is an inverted cylinder or tank placed within the tank A, it being raised from and connected with the bottom of the said tank by legs P. Cylinder O has a pipe, Q, extending nearly to the top of the tank A, and provided with a bracket, R, to which is pivoted a lever, S, having a valve, T, which serves to close the upper end of the pipe Q in an air-tight man-

ner. The end of lever S carries a float, U, the weight of which normally serves to press the valve T against the opening of pipe Q, keeping the latter closed.

Inside the inverted tank O is a float, V, which is connected with the lever L, for the purpose of regulating the valves M N, as will be hereinafter described. The top of the tank A has an air-inlet pipe, W, adjoining which is a downwardly-extending bracket, Y, to which is pivoted a lever, Z, having a valve, A², which closes the said inlet.

To the lever Z is pivoted a rod, X, which extends downwardly through suitable guide-brackets, B², attached to the inverted tank O, and reaching to within a short distance of the lever L, so that when the latter is raised by the action of the float V it shall strike against the said rod X and cause the valve A² to be opened. The lever Z of the air-inlet valve also extends over the end of the lever S, so that when the latter is raised by the action of the float U it shall strike against the said lever Z and cause the valve A² to be opened. A guide-rod, C², extends through and downwardly from the float U and through the upper guide-bracket, B², for the purpose of holding the said float steady during operation. The top of tank A has an air-exit pipe, D², connected by a pipe, E², with a tight receptacle—such as, for instance, a keg of beer. The pipe D² has a check-valve, F², which will permit the compressed air to pass out, but will prevent its back-flow.

The operation is as follows: The valves N, A², and T being closed, and water being allowed to enter at the inlet I, it will, by rising in the cylinder A, compress the air therein. Owing to the air confined in the tank O, the water will only rise for a short distance in the said tank, and not high enough to lift the float V, and even if the water should rise high enough to submerge the float the latter will not have sufficient buoyancy to overcome the downward pressure upon the waste-valve N. The water will rise till it reaches the float U, which will of its own buoyancy lift and open the valve T by means of the lever S. This lets the air confined within the tank O escape into the larger cylinder, and allows the water to enter

the tank O from below and entirely submerge the float V. The latter, however, will not have sufficient buoyancy to overcome the pressure now existing upon the waste-valve N. The 5 float U continues to rise until it reaches the lever Z, which opens the valve A², permitting a portion of the compressed air to escape. The pressure upon the waste-valve being thus relieved, the float V will instantly rise, thus opening the waste-valve N and closing the inlet-valve M. It also retains the inlet-valve A² in an open position by the action of the lever L, rod X, and lever Z. The water will run out of the cylinder A at the waste-pipe J. As it 10 lowers, the float U will sink, thus closing the valve T, making the top of the inverted tank O air-tight. The water will continue to escape from the tank A, but remains suspended in the tank O, thus retaining float V in a raised 15 position. The water descends till it reaches the lower edge of the tank O, which will then be suddenly emptied, thus causing the float V to drop, closing the waste-valve N, opening the water-inlet, and causing the air-inlet to be 20 closed, thus placing the apparatus in position 25 for a repetition of the operation.

I claim as my invention and desire to secure by Letters Patent of the United States—

1. In a hydraulic air-compressor, the combination of a closed cylinder or tank provided in its bottom with a water-inlet and a waste-pipe, a lever provided at its respective ends with valves adapted to close the said inlet and waste pipe, a closed inverted tank placed within the 30 said main cylinder, a float located within the 35 said tank, and connected with and adapted to operate the lever controlling the inlet and waste openings, means for automatically establishing communication between the inverted tank and 40 the main tank when the water rises in the latter, and means for automatically opening an air-inlet valve at the top of the main tank, substantially as set forth.

2. The combination of the closed main tank, provided at its bottom with inlet and waste 45 pipes, an inverted tank arranged within the said main tank, with the bottom of which it is securely connected by means of suitable supporting-legs, a float located within the said inverted tank, a lever connected with and operated by the said float, and provided at its ends with valves adapted to close the inlet and waste openings, and tank U, with connected valve T, substantially as set forth.

3. In a hydraulic air-compressor, the combination of the closed main tank, provided in its bottom with inlet and waste pipes, an inverted tank placed within the main tank, and having a pipe extending nearly to the top of said main tank, a lever provided at its ends with 60 valves adapted to close the inlet and waste pipes, a float located within the inverted tank and connected with and operating the said lever, a lever fulcrumed at the upper end of the pipe, extending upwardly from the inverted tank, 65 and having a valve adapted to close the said pipe, a float at the end of the said lever, an air-inlet in the upper part of the main tank, a lever having a valve adapted to close the said air-inlet, and provided with a rod extending downwardly to within a short distance of the lever 70 controlling the water-inlet and waste-pipe, said air-inlet-controlling lever being extended over and adapted to be operated by the lever fulcrumed at the top of the pipe, extending upwardly from the inverted tank, and an air-outlet arranged in the upper part of the main tank, and having a check-valve, substantially as and for the purpose set forth.

In testimony that I claim the foregoing as my 80 own I have hereto affixed my signature in presence of two witnesses.

CHAS. HORACE HILL.
